(57) **CLAIM**

The ornamental design for a cigarette making machine, as
shown and described.

DESCRIPTION

FIG. 1 is a perspective view of a cigarette making machine
according to the present invention;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines show portions of a cigarette making
machine that form no part of the claimed design.
